UNITED STATES PATENT OFFICE

137,159

DESIGN FOR A COMBINATION SHELF AND DRYING RACK

John E. Borah, Penn Township, St. Joseph County, Ind.

Application April 26, 1943, Serial No. 110,044

Term of patent 14 years

To all whom it may concern:

Be it known that I, John E. Borah, a citizen of the United States, residing at Penn township, in the county of St. Joseph, State of Indiana, have invented a new, original, and ornamental Design for a Combination Shelf and Drying Rack, of which the following is a specification, reference being had to the accompanying drawing, forming part thereof.

Fig. 1 is a top front perspective view of the combination shelf and drying rack, showing my new design.

Fig. 2 is a bottom front perspective view thereof.

I claim:

The ornamental design for a combination shelf and drying rack, as shown.

JOHN E. BORAH.
